(No Model.)

H. G. & W. BUTLER.

FEEDING APPARATUS FOR USE IN BURNING CLAY.

No. 447,459.

Patented Mar. 3, 1891.

UNITED STATES PATENT OFFICE,

HENRY G. BUTLER AND WILLIAM BUTLER, OF KENOSHA, WISCONSIN.

FEEDING APPARATUS FOR USE IN BURNING CLAY.

SPECIFICATION forming part of Letters Patent No. 417,459, dated March 3, 1891.

Application filed August 22, 1890. Serial No. 362,736. (No model.)

To all whom it may concern:

Be it known that we, HENRY G. BUTLER and WILLIAM BUTLER, citizens of the United States, residing at Kenosha, in the county of Kenosha and State of Wisconsin, have invented 5 a new and useful Improvement in Feeding Apparatus for Use in Burning Clay, of which the following is a specification.

Our invention relates to an improvement in the class of apparatus set forth in Letters Patent of the United States Nos. 389,551 and 413,361, granted, respectively, to William Davy on the 18th day of September, 1888, and to William Davy and Henry G. Butler on the 15 22d day of October, 1889; and though we wish to claim our present improvement for any purpose to which it may be applicable we have especially designed it for use as a labor-saving machine in burning clay to make balls last according to the United States Patents 20 Nos. 305,432 and 371,042 to William Davy and our own Letters Patent No. 413,358. A general description of the manner of procedure observed under the said Letters Patent 25 for burning clay, and in the practice of which we use feeding apparatus, may be here briefly stated to enable the more ready understanding of the manner of employing our present improvement. The clay is burned in the open 30 air and on the ground from which the supply is taken, being dug from a trench (formed by the removal of the supply of clay) and piled along one side thereof to form the "fire," which is of long extent, and which is replenished with alternate layers of fuel and clay, 35 the latter being supplied by a feeding apparatus, a general description of which as hitherto employed, and as shown and described in the aforesaid Letters Patent No. 413,361, is as follows: Along the side of the trench or line 40 from which the clay for burning is dug and opposite the side thereof along which the fire extends a railroad is provided for a car supporting the feeding apparatus and means for 45 actuating and controlling it, the feeding mechanism involving a boom extending laterally from the car over the work or fire and a scoop or scraper supported on and controlled through the medium of cables from winding mechanism 50 is inside the car to fill itself with clay by scooping it along the side of the trench adja-

cent to the track and carry it out toward and dump it upon the fire.

Our present improvement relates particularly to the means for supporting and controlling the scoop or scraper, and which are illustrated in the accompanying drawings, in which—

Figure 1 is a view in elevation, partly sectional, showing the feeding apparatus provided with our improvement; and Fig. 2, a section taken on the line 2 of Fig. 1 and viewed in the direction of the arrow.

A is the support, preferably in the form of a car movable on a track extending along one side of the fire, the car carrying on its roof the frame-work or "mast" B, and from the base of which extends laterally of the car the boom C, and D is the scraper or scoop. These parts may involve the construction set forth in the last-named Letters Patent or in the application of Henry G. Butler, Serial No. 362,735, filed August 22, 1890, and need not, therefore, be more definitely described in the present connection, or they may involve any other suitable construction. The boom C may, however, be especially adapted for the travel upon it of the scoop-carrying carriage E, and to that end should have the two sides r and r' forming it constitute a track upon which the carriage is supported.

The carriage E may be a four-wheeled vehicle, as shown, on a suitable truck p, from which is suspended a pulley q on a rod o. From the pulley q is suspended the scoop or 85 scraper D by a cable n led inside the car A over a guide-pulley n' and there fastened to an operating-drum m. The drum l inside the car controls the scooping operation of the device D by being connected with the latter 90 at its forward end through the medium of the cable k, while the cable i connects the carriage from its forward end with the drum h inside the car, passing thereto over the pulley g at the end of the boom and over the 95 pulley f at the top of the mast or frame B. The power mechanism inside the car may be that shown and described in the aforesaid formerly-patented apparatus, and need not, therefore, be shown and described in the 100 present application.

The operation is as follows: The cable n

should be so adjusted as to its length by winding it upon or from the drum *m* as to cause it to allow the scraper *D* to enter the trench to the desired depth for loading itself 5 with the clay and permit it to be extended to the desired point for dumping on the fire. The filling is accomplished in the old manner—namely, by turning the drum *l* to pull the scoop *D* in the proper direction when it 10 has been lowered into the trench. When filled, the drum *h* is turned to wind upon it the cable *i*, thereby drawing the carriage *E* on its track toward the outer end of the boom *C*, and thus to the point over the fire at which to 15 dump it. As the carriage proceeds on its outward course it carries with it the laden scoop or scraper *D*, which, by the consequent lengthening out in the direction of travel of the carriage, conveys the scoop or scraper up an 20 inclined plane to the point of dumping. After the scraper has been dumped it is returned and lowered to be again filled by moving under the influence of the gravity of the carriage *E* down the inclined track into the 25 trench, assuming the position in which it is illustrated in the drawings.

Obviously a suitable track for the carriage may be formed, as shown and described, by the boom itself, or may be attached to the 30 boom.

By doubling the cable *n*, as indicated in Fig. 1, the vertical rise of the scraper may be regulated to any desired proportion of the movement thereof toward the fire.

35 What we claim as new, and desire to secure by Letters Patent, is—

1. In an apparatus substantially for the purpose set forth, the combination of a support *A*, provided with winding-drums *l*, *m*, and *h*, and carrying a mast *B*, a boom *C*, having a track extending lengthwise along it and rising toward its outer end, a carriage *E*, supported on the track and connected from its forward end by a cable *i* with the drum *h*, a scoop or scraper *D*, suspended from the carriage by a cable *n*, connected with the drum *m*, and a cable *k*, connecting the device *D* from its forward end with the drum *l*, substantially as described. 40

2. In an apparatus substantially for the purpose set forth, the combination of a car *A*, provided with winding-drums *l*, *m*, and *h*, and carrying on its roof the mast structure *B*, a boom *C*, extending from the car and provided with a track rising toward the outer end of the boom, a carriage *E* on the track, connected from its forward end by a cable *i* with the drum *h* and provided with a suspension-rod *o*, carrying a pulley *q*, a scoop or scraper *D*, suspended from the pulley *q* by a cable *n*, 55 connected with the drum *m*, and a cable *k*, connecting the device *D* from its forward end with the drum *l*, the whole being constructed and arranged to operate substantially as described. 60

HENRY G. BUTLER.
WILLIAM BUTLER.

In presence of—

J. W. DYRENFORTH,
M. J. FROST.
